By Monroe Miller

UNITED STATES PATENT OFFICE.

CARL ANTON CARLSON, OF FORT DODGE, IOWA.

AUTOMATIC GARAGE-DOOR OPENER.

Application filed August 7, 1924. Serial No. 730,612.

To all whom it may concern:

Be it known that I, CARL ANTON CARLSON, a citizen of United States, residing at Fort Dodge, in the county of Webster and State of Iowa, have invented certain new and useful Improvements in an Automatic Garage-Door Opener, of which the following is a specification, reference being had therein to the accompanying drawing.

10 The present invention relates to automatic door openers, and aims to provide a novel and improved automatic mechanism for opening the doors of a garage or other building when an automobile approaches the 15 doors, so as to relieve the operator from stopping the machine and getting out for opening the doors.

Another object of the invention is the provision of a novel and improved tread mechanism over which the vehicle runs when approaching the doors and operatively connected with the doors for automatically opening said doors.

25 A further object of the invention is the provision of such a mechanism including a novel construction and assemblage of the component elements to enhance the utility and efficiency of the mechanism.

With the foregoing and other objects in view, which will be apparent as the invention proceeds, the invention resides in the construction and arrangement of parts, as hereinafter described and claimed, it being understood that changes can be made within 35 the scope of what is claimed, without departing from the spirit of the invention.

The invention is illustrated in the accompanying drawings, wherein—

40 Figure 1 is a plan view of the mechanism, showing the doors in horizontal section, and portions being removed.

Fig. 2 is a vertical longitudinal section on the line 2—2 of Fig. 1.

45 Fig. 3 is a cross section on the line 3—3 of Fig. 1.

Fig. 4 is a sectional detail on the line 4—4 of Fig. 1.

Fig. 5 is a transverse vertical section illustrating a modification.

50 Fig. 6 is a vertical section on the line 6—6 of Fig. 5.

Fig. 7 is a view similar to Fig. 5 showing another modification.

55 Fig. 8 is a horizontal section on the line 8—8 of Fig. 7.

As shown in Figs. 1, 2, 3 and 4, the im-

provements are used in connection with the hinged doors 11, and the floor of the garage and run-way or drive-way in front of the garage, which may be of concrete, wood, brick or other material, is provided with the parallel longitudinal pits 12 extending under the doors in the paths of the wheels of the vehicle as it moves into and out of the garage. The tread mechanisms are disposed in said pits, as will presently appear.

The tread device within each pit or channel 12 comprises an intermediate tread plate 13 and end tread plates 14, and the rim of each pit or channel is preferably protected by the angle irons 15. The tread plates 13 and 14 are depressible, and the depression of said plates is used for opening the doors. The plates 13 and 14 are secured on the respective parallel longitudinal beams 16 and 17, which are preferably of I cross section, and which are connected at their lower edges or flanges by cross bars 18. The intermediate plate 13 of each set is shorter than the beams 16, and the plates 14 project beyond the inner ends of the beams 17 to overlap the end portions of the beams 16, so that the plates 14 are supported at their inner ends from the beams 16 of the intermediate plate, with the plates 14 free to slide and swing relatively to the plate 13.

55 The plates 14 are hingedly supported at their opposite or outer ends. Thus, the outer ends of the beams 17 have notches or slots 19 engaging transverse hinge rods 20 secured within the end portions of the pit or channel 12. By moving the beams 17 longitudinally the notches 19 are readily engaged with the rods 20, and the beams 17 can then swing downwardly between the beams 16 and ends of the pit with the plates 14 seating on the beams 16. The intermediate tread plate 13 in each pit is supported for vertical movement.

For this purpose, transverse shafts 21 and 22 extend across each pit or channel, and are journaled in bearings 23 disposed at the opposite sides of the pit, said bearings being preferably secured to the angle irons 15. Downwardly extending arms 24 have clamps 25 embracing the shafts 21 and 22, and upwardly diverging bars 26, arranged in pairs, are secured near their lower ends to the arms 24, and transverse pivot rods 27 extend through the upper terminals of the pairs of bars 26 and have their terminals engaging within notched members 28 secured to the beams 16. The beams 16

are thus seated on the rods 27 which are offset longitudinally relatively to the corresponding shafts 21 and 22, to mount the plate 13 for vertical movement. Pairs of brace bars 29 engage the rods 20 and shafts 21 and 22 at the opposite sides of the arms 24 and bars 26. The lower terminals of the bars 26 extend below the arms 24 and straddle a longitudinal bar 30, said bars 26 being pivoted to said bar 30, as at 31. The arm 24 and bars 26 and 29 provide levers supporting the tread plate 13 and connected to the connection bar 30, whereby the levers turn simultaneously, thereby constraining the plate 13 to remain level or horizontal.

The tread plate 13 is normally raised by a spring 32 connected to the bar 30 to move said bar in one direction so as to raise the beams 16 and plate 13. As shown, the coiled spring is used, having one end connected to the bar 30, and its other end connected to a cross bar 33 secured in the pit 12.

The upward movement of the plate 13 is limited by an adjustable stop screw 34 against which one end of the bar 30 abuts when said bar is moved by the spring 32 to raise the plate 13. As shown, the screw 34 is adjustable in a stud 35 rising from the bottom of the pit, and said screw can be adjusted to properly limit the upward movement of the tread plates. If desired, the plates 13 and 14 can be flush with the floor when the doors are closed.

The two tread devices are operatively connected with the doors 11. Thus, the shaft 22 is common to both tread devices, and extends transversely across both pits 12 and through secondary pits or recesses 36 in the floor adjacent to the hinged edges of the doors. Tubes or pipes 37 are preferably embedded in the floor structure between the pits to receive the shaft 22, and the opposite ends of said shaft are journaled in bearings 38 disposed at the outer sides of the pits 36. The shaft 22, which is turned by either or both of the tread devices, is operatively connected with both doors 11. Thus, upwardly extending arms 39 have clamps 40 tightly embracing the shaft 22 within the pits 36, and said arms are connected by links 41 with the doors 11. The links are adjustable in order to regulate the opening of the doors. Thus, each link comprises the sections 42 and 43 having the slotted adjustable connection 44, and the sections 42 and 43 have ball and socket connections with the corresponding arm 39 and door 11, respectively.

The mechanism will operate to open the doors when the vehicle moves toward the doors from either side, either when moving out of or when entering the garage. Thus, when the wheels of the vehicle move onto the tread plates 14 at either end, said plates are depressed, thereby depressing the beams 16, and the shaft 22 being turned will swing

the arms 39 so as to shove the links 41 in a direction to swing the doors 11 open. The vehicle can then pass through the doorway, and the doors will be held open as long as one pair of wheels is on the tread plates. As the last pair of wheels roll off the tread plates, the springs 32 will restore the parts to normal position, thereby automatically closing the doors.

Figs. 5 and 6 illustrate a modification for use with horizontally sliding doors 11^a. Thus, the arms 39^a which are secured on the operating shaft 22^a within the pits or recesses 36^a are connected by links 41^a with the short arms 46 of bell crank levers fulcrumed, as at 47, within the recesses 36^a, and having the long upwardly projecting arms 48 operatively connected with the doors, the arrangement being such that when the tread plates are depressed, the shaft 22^a is turned to raise the arms 39^a and swing the bell crank levers to move the arms 48 away from one another to slide the doors open. The arms 48 pass slidably through studs 49 pivotally connected with plates 50 secured to the doors, so that the arms can slide through the studs 49, and to enable said studs to turn with the arms 48 as the doors are slid open and closed.

Figs. 7 and 8 illustrate a further modification for use with a vertically slidable door 11^b. Levers 48^b extend across the outer and inner sides of the door and have the fulcrum portions 47^b journaled for rotation through the jambs or side posts 51 of the door frame near the upper edge of the door. Said levers 48^b are slidable through studs 49^b swivelled to plates 50^b secured to the opposite sides of the door, whereby the oscillation of the levers 48^b will slide the door vertically to open and closed positions. The arms 29^b on the operating shaft 22^b are connected by links 41^b with the levers. One link 41^b is connected directly to the corresponding lever 48^b, while the other lever has a short arm 46^b to which the other link 41^b is connected, so that both links can be at the same side of the door. Each link 41^b comprises sections or bars 42^b and 43^b having their adjacent terminals overlapped and slidably connected. Thus, bolts 44^b are carried by the section or bar 42^b and work in a longitudinal slot 44' in the section or bar 43^b, whereby the link can be lengthened and shortened.

When the shaft 22^b is turned by the depression of the tread members, the arms 39^b are raised, thereby raising the links 41^b and swinging the levers 48^b upwardly to slide the door open.

Having thus described the invention, what is claimed as new is:—

1. A mechanism of the character described comprising intermediate and end tread members, the inner ends of the end

members resting on the end portions of the intermediate member, hinge rods mounted at the outer ends of the end members, said outer ends of the end members having slotted portions to detachably engage said hinge rods by the movement of the end members away from the intermediate member, said end members being located between said hinge rods and intermediate member, 5 means for supporting the intermediate member for vertical movement, and an operative connection for connecting said intermediate member with a door for opening the door when said intermediate member is depressed.

10 2. A mechanism of the character described comprising intermediate and end tread plates, beams on which said plates are secured, the inner ends of the end plates resting on the beams of the intermediate plate, hinge portions at the outer ends of the end plates, the beams of the end plates having slotted portions to detachably engage said hinge portions, means for supporting the beams of the intermediate plate for vertical movement, and an operative connection for connecting the beams of the intermediate plate with a door for opening the door when said intermediate plate is depressed.

15

In testimony whereof I hereunto affix my signature.

CARL ANTON CARLSON.
